Primary Examiner—Cathron C Brooks*Assistant Examiner*—Melanie Levy(74) *Attorney, Agent, or Firm*—Cermak Nakajima LLP;
Tomoko Nakajima(57) **CLAIM**

The ornamental design for a ring with surface ornamentation, as shown and described.

DESCRIPTION

FIG. 1 is a perspective view of a ring with surface ornamentation showing my new design; and

FIG. 2 is a plan view thereof in flattened form; and,

FIG. 3 is a top plan view thereof, a bottom plan view thereof being a mirror image.

The broken lines shown in drawings are for illustrative purposes only and form no part of the claimed design.
